UNITED STATES PATENT OFFICE.

ZANZIE EDWARDS, OF CLARKSVILLE, TENNESSEE.

PIPE CLEANER.

Application filed February 19, 1925. Serial No. 10,245.

To all whom it may concern:

Be it known that I, ZANZIE EDWARDS, a citizen of the United States, residing at Clarksville, in the county of Montgomery and State of Tennessee, have invented certain new and useful Improvements in a Pipe Cleaner, of which the following is a specification.

The present invention relates generally to pipe cleaners, and more particularly to cleaners for ammonia pipes in refrigeration systems and the like.

The important object of the invention is to provide a cleaner of this nature which is efficient in use on the outside surfaces of pipes.

Another important object of the invention is to provide a cleaner of this nature which is strong, durable, and well adapted to the purpose for which it is designed.

The invention further aims to provide a device which is easy to use and one which will not dig into the pipe or damage it.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the cleaner showing the same in use,

Figure 2 is a transverse section thereof, and

Figure 3 is an end elevation of the cleaner.

Referring to the drawing in detail it will be seen that the body of the cleaner is indicated generally by the letter A and is of a formation having circular ends 5 and 6, the latter being greater in diameter than the former. The periphery between the ends

5 and 6 tapers from these ends toward its intermediate portion so that the surface may be said to be arcuate. This surface is provided with a plurality of arcuate grooves forming the arcuate teeth or cutting edges 7. In the preferred construction of this invention the arc of each tooth is slightly greater than ninety degrees. A stud shaft 8 extends axially from the body at the end 6 and is adapted to be engaged by suitable operating means for rotation thereof and the body.

With this cleaner, the operator may move the same longitudinally of the pipe from end to end in four different places as indicated to advantage in Figure 1, thereby completely cleaning the outer surface of the pipe.

The present embodiment of the invention which I have described in detail has been given merely by way of example. It is to be understood that these cleaners may be made in numerous sizes and in numerous different proportions. It is also evident that numerous other changes in the details of construction, in the material, and in the combination and arrangement of parts may be resorted to as do not depart from the spirit or scope of the invention as herein-after claimed.

Having thus described the invention, what I claim as new is:—

A cleaning device of the class described including a body having circular ends, one smaller in diameter than the other and a plurality of concave teeth on the surface extending longitudinally between the ends the body being smaller at an intermediate portion than at either end, and a stud shaft extending from the larger end axially of the body.

In testimony whereof I affix my signature.

ZANZIE EDWARDS.
